(57) **CLAIM**

The ornamental design for a display screen or portion
thereof with icon, as shown and described.

DESCRIPTION

A portion of the disclosure of this patent document contains
material which a claim for copyright is made. The copyright
owner has no objection to the facsimile reproduction by
anyone of the patent document or the patent disclosure, as it
appears in the U.S. Patent and Trademark Office patent file
or records, but reserves all other copyrights whatsoever.
The FIGURE is a front view of a display screen or portion
thereof with icon.

The broken lines depict portions of a display screen or
portion thereof that form no part of the claimed design.
